UNITED STATES PATENT OFFICE.

WILLIAM E. BAKER, OF ROCK ISLAND, ILLINOIS.

FLUID-PRESSURE ENGINE.

1,391,446.

Specification of Letters Patent. Patented Sept. 20, 1921.

Application filed March 5, 1920. Serial No. 363,537.

To all whom it may concern:

Be it known that I, WILLIAM E. BAKER, a citizen of the United States, residing at Rock Island, in the county of Rock Island 5 and State of Illinois, have invented certain new and useful Improvements in Fluid-Pressure Engines, of which the following is a specification.

This invention relates to a fluid pressure 10 engine and its object is primarily to balance the pressure distributing valve in such a manner that it will automatically adjust itself as the pressure varies to avoid corresponding variation in friction and thereby 15 insure proper and efficient distribution of the pressure fluid to the cylinders in a desired manner.

A further object of the invention is to 20 provide means whereby the distribution of fluid pressure to the cylinders may be varied as to time and as to volume to accommodate varying loads on the engine without varying the flow of the pressure of the fluid during the time that it is being distributed.

25 A further object of the invention is to provide simple means for changing the lead of the distributing valve from time to time so that as the engine speed increases or decreases the admission of pressure fluid to 30 the cylinders may be correspondingly varied.

Further objects of the invention are to 35 provide a balance valve which can be easily adjusted for forward or reverse operation of the engine; which will avoid back pressure in the cylinders by automatically opening the cylinders to the atmosphere on the return stroke of the pistons and still preserve sufficient pressure in the cylinders to 40 cushion the pistons; and which can be embodied in a simple and efficient manner in all kinds of rotary and stationary engines.

In the accompanying drawings I have 45 illustrated the balanced distributing valve in a selected embodiment and incorporated in a rotary engine, but I do not limit myself to this particular embodiment or installation as will more fully appear hereinafter.

Figure 1 is a sectional view of the distributing valve on the line 1-1 of Fig. 2.

Fig. 2 is a sectional end elevation of the distributing valve partly broken away and taken on the line 2-2 of Fig. 1.

Fig. 3 is a sectional side elevation of the 55 distributing valve partly broken away.

Fig. 4 is a detail plan view of the bridge plate.

Fig. 5 is a detail view of the pressure control levers.

Fig. 6 is an end elevation, partly in section and partly broken away, and Fig. 7 is a side elevation, partly in section, showing a rotary engine embodying my invention; and

Figs. 8 and 9 are similar views showing a slightly different construction of rotary 65 engine embodying the invention.

Referring to the drawings, in which like numerals of reference indicate corresponding parts in the several figures, the balance valve comprises the body 1 which is divided 70 at 2 and is arranged within a bushing 3, said bushing having a plurality of ports 4 which register with elongated ports 5 in the valve body (Fig. 2). The ports 4 conform in area with the area of the cylinders, they 75 are spaced apart equally, and they correspond in number with the engine cylinders. The ports 5 are located in adjacent relation and are governed as to number and size by the number of cut-off points desired and this 80 depends, as is well known in engine practice, upon the character of work the engine is built to perform. Angle pins 6 are pivotally engaged with ears 7, 7' on the valve body and they have telescopic engagement 85 with radial sockets 8 on the pressure inlet pipe 9 whereby the valve body is permitted to expand and contract without affecting the inlet tube upon which it is supported.

A lever in the form of a yoke comprising 90 two members 10, 10' arranged side by side is pivotally engaged with the ears 7, 7' on the valve body by pins 11 which are seated in said ears and in the ends of the yoke lever (Figs. 1, 5). The other end of the yoke 95 lever is pivotally engaged at 12 with the connecting rod 13 which is provided at its other end with the cross pin 14 by which it is pivotally engaged with the piston 15 arranged to operate in a cylinder 16 formed in 100 the valve body. A connecting yoke 17 is pivotally connected at 18 to ears 19 on the valve body and at 20 to oppositely disposed bosses 21 on the yoke lever members 10, 10'. The ears 7, 7' and the ears 19 are located 105 adjacent to the ends 2 of the divided valve body and on opposite sides thereof so that the valve body can be readily contracted or expanded by the pressure control mechanism to preserve the proper frictional en-

110

gagement of the body with the bushing under all pressure conditions.

A bridge plate 22 (Figs. 2, 4) is yieldingly held by bolts 23 and springs 24 in place within a seat 22' in the valve body over the slot between the ends 2 of the body, and keys 25 are seated in said ends adjacent the sides of the valve body to prevent leakage of pressure lengthwise of the slot from within the valve body to the engine cylinders. This bridge plate is held by the pressure within the valve body snugly against the ends 2 of the body and effectually seals the slot between said ends and prevents leakage of pressure through the slot in a direction radial of the body. It will be readily understood by reference to Fig. 2 that as pressure increases within the valve body it will act upon the piston 15 and operate the release mechanism comprising the lever yoke and the connecting yoke 17 to hold the valve body against the tendency of the pressure to expand the same, thus utilizing that pressure to operate the mechanical means for adjusting the valve body to compensate for any increase or decrease of pressure. It will be clearly apparent that as the valve body and bushing wear in actual use the valve body will automatically expand to compensate for such wear thereby insuring a proper fit of these working parts at all times and under all pressure conditions. The predetermined relation of the valve body and the bushing is constantly maintained regardless of wear and variations in pressure, and thereby I avoid leakage due to wear and looseness of fit and also avoid any increase in friction between these parts which might otherwise be due to an increase of pressure.

A variable cut-off plate 26 is pivotally mounted on an arm 27 within the valve body and this arm is rigidly mounted on an operating rod 28 located within the pressure inlet tube 9. A handle lever 29 is provided on the outer end of the rod 28 whereby the rod can be rocked in its bearings in the tube to adjust the cut-off plate as desired. This cut-off plate is segmental in shape to fit the inner wall of the valve body 1 and the connection 27' between the arm 27 and the plate is somewhat loose to provide for wear on the plate. It will be understood, of course, that the pressure within the valve body will hold the plate in operative engagement with the valve body regardless of this loose connection. The cut-off plate is of a size adapted to cut off all of the ports 5 in the valve body, and it is quite apparent that by operating the handle lever 29 the plate can be adjusted to cut off one or more of the ports 5 as may be desired to properly proportion the pressure to the load. It will be understood, however, that while the cut-off plate may be adjusted to vary the distribution of fluid pressure as to time and as to volume to accommo-

date varying loads on the engine, the flow of the pressure of the fluid during the time that it is being distributed to the cylinders is not in any way diminished. It will also be apparent that the plate can be used to cut off all of the ports 5 and thereby stop the engine in any emergency which might prevent proper manipulation of the throttle.

The outer wall of the body is cut out to provide a passage 30 located opposite the ports 5 in proper relation thereto to enable the escape of pressure from the cylinders on the return stroke of the pistons. When the pistons 31 (Figs. 6, 8) passes ports 32 on its return stroke, the pressure within the cylinder 33 above the piston passes out through the passage 34 and through the passage 30 in the valve body to the following cylinder in front of the piston therein and thence through the ports 32 in that cylinder into the chamber 35 in the engine casing 36, from which it is permitted to escape through an outlet 37. Thus, in a very simple manner, back pressure in the engine cylinders is entirely avoided and consequent loss of power is entirely overcome.

My balance valve may be incorporated in rotary or stationary engines of all kinds so far as I know, with such changes and modifications as may be necessary or desirable to adapt it for a particular installation. A rotary engine of two slightly different constructions and having my valve embodied therein is illustrated in Figs. 6 to 9, and referring thereto the engine cylinders 33 are mounted in a crank case 38 in which the balance valve is also arranged. In the construction of Figs. 6 and 7 power is transferred to a propeller shaft 39, and in the construction of Figs. 8 and 9 power is transferred through a gear 40. The bushing 3 is securely held in the crank case to revolve therewith about the valve body.

Fig. 2 shows a valve arranged in position for clockwise movement of the crank case and forward operation of the engine; to reverse the movement of the crank case and the engine I operate the handle lever 29 to advance the cut-off plate 26 to the opposite side of the ports 5 and then shift the position of the valve body within the bushing by operating the handle lever 41 to the other side of the dead center. It will be observed that this change of direction of operation of the engine is effected in a very simple manner without the aid of gears, eccentrics or links, thereby avoiding all complications of mechanism and the consequent liability of wear and breakage.

I have found that my invention enables me to produce an engine very much lighter in weight for a given horse power than has heretofore been possible, so far as I am aware, due to the simple and compact construction of the valve mechanism and the

engine construction. For this reason and because it can be so easily operated and is so free from liability of getting out of order, it is especially adapted for automobile use. A steam engine constructed in accordance with my invention can be operated at low or high speed, and because it is light in weight and can be run efficiently at high speed, I believe it is well adapted for airplane use. My invention is also adapted for marine engines, tractor engines and stationary engines of all kinds so far as I am at present aware. The pressure control mechanism for adjusting the valve body is automatically operated by the pressure within the valve body to maintain the valve body in its proper relation to the bushing so that there will be no material variation in friction due to changes in pressure. Furthermore, this automatic adjustment takes care of any wear between the valve body and the bushing so that these parts will always be maintained in their proper relation. I am aware that it will be necessary to change the construction and proportion and arrangement of the details of my invention to adapt it for different installations, and I therefore reserve the right to make all such changes and modifications as fairly fall within the scope of the following claims.

I claim:

1. A distributing valve for fluid pressure engines comprising a valve body in the general form of a divided ring and adapted to receive fluid under pressure therein and having outlet ports, and means engaged with the ends of said body and adapted to be operated by the fluid within the body for automatically adjusting said body to compensate for wear and to prevent tendency of the body to expand under pressure of the fluid within the body.
2. A distributing valve for fluid pressure engines comprising a valve body in the general form of a divided ring and adapted to receive fluid under pressure therein and having outlet ports, and means pivotally engaged with said ring adjacent the ends thereof and adapted to be operated by the fluid within the body for automatically adjusting said body to compensate for wear and to prevent tendency of the body to expand under pressure of the fluid within the body.
3. A distributing valve for fluid pressure engines comprising a valve body in the general form of a divided ring and adapted to receive fluid under pressure therein and having outlet ports, and means comprising lever devices engaged with said ring adjacent its ends and piston means adapted to be operated by the fluid within the body for actuating said lever devices to prevent any material increase of friction by expansion of the body due to the pressure of the fluid within the body.

4. A distributing valve for fluid pressure engines comprising a valve body in the general form of a divided ring and adapted to receive fluid under pressure therein and having outlet ports, and means comprising ears projecting inwardly from the ring adjacent the ends thereof, lever devices pivotally engaged with said ears and with each other, and a piston pivotally connected with said lever devices and operated by the fluid within the valve body to control said lever devices and prevent the valve body from expanding under pressure of the fluid within the body.

5. A distributing valve for fluid pressure engines comprising a valve body in the general form of a divided ring and adapted to receive fluid under pressure therein and having outlet ports, and means comprising lever devices engaged with said ring adjacent its ends, a cylinder formed in one side of the ring, and a piston in said cylinder connected with said lever devices and operated by the fluid within the valve body to control said lever devices and prevent expansion of the valve body under pressure of the fluid within the body.

6. A distributing valve for fluid pressure engines comprising a valve body in the general form of a divided ring and adapted to receive fluid under pressure therein and having outlet ports, a tube for admitting fluid to the ring, adjustable connections between said ring and tube, and means adapted to be operated by the fluid within the body for automatically adjusting said body to compensate for wear and to prevent material expansion of the body under pressure of the fluid within the body.

7. A distributing valve for fluid pressure engines comprising a valve body in the general form of a divided ring and adapted to receive fluid under pressure therein and having outlet ports, a tube for admitting fluid to the ring, and connections between the ring and tube pivotally engaged with the ring and telescopically engaged with the tube.

8. A distributing valve for fluid pressure engines comprising a valve body in the general form of a divided ring and adapted to receive fluid under pressure therein and having outlet ports, a tube for admitting fluid to the ring, and connections between the ring and tube comprising ears on the ring and sockets on the tube and pins pivotally engaging said ears and telescopically engaging said sockets.

9. A distributing valve for fluid pressure engines comprising a valve body in the general form of a divided ring and adapted to receive fluid under pressure therein and having outlet ports, a cut-off plate arranged within the valve body, and means for operat-

ing said plate to vary the fluid outlet from said valve body.

10. A distributing valve for fluid pressure engines comprising a valve body in the general form of a divided ring and adapted to receive fluid under pressure therein and having outlet ports, a variable cut-off plate arranged within the valve body and conforming with the curvature thereof at the outlet ports, and means for operating said plate to vary the fluid outlet from said body.

11. A distributing valve for fluid pressure engines comprising a valve body in the general form of a divided ring and adapted to receive fluid under pressure therein and having outlet ports, a variable cut-off plate rotatable within the valve body over the outlet ports, and means for adjusting said plate to vary the fluid outlet from the body.

20. 12. A distributing valve for fluid pressure engines comprising a valve body in the general form of a divided ring and adapted to receive fluid under pressure therein and having outlet ports, a variable cut-off plate conforming with the curvature of the inner wall of the valve body at the outlet ports and rotatably movable within said body, an arm radially disposed within the valve body and loosely connected with said plate, and means connected with said arm for adjusting said plate to vary the fluid outlet from the valve body.

35. 13. A distributing valve for fluid pressure engines comprising a valve body in the general form of a divided ring and adapted to receive fluid under pressure therein and having outlet ports, a tube for admitting fluid to said valve body, a variable cut-off rotatably movable within said valve body over 40 the outlet ports, a rod located within said tube, an arm rigid with said rod and loosely engaged with said plate, and means for operating the rod to adjust the plate for varying the fluid outlet.

45. 14. A distributing valve for fluid pressure engines comprising a valve body in the general form of a divided ring and adapted to receive fluid under pressure therein and having outlet ports, and means for preventing 50 the escape of fluid between the ends of said ring.

55. 15. A distributing valve for fluid pressure engines comprising a valve body in the general form of a divided ring and adapted to receive fluid under pressure therein and having outlet ports, and means for preventing the escape of fluid between the ends of said body comprising a plate bridging the space between the ends of said body and held by 60 fluid pressure within the body against the inner wall thereof.

65. 16. A distributing valve for fluid pressure engines comprising a valve body in the general form of a divided ring and adapted to receive fluid under pressure therein and hav-

ing outlet ports, and means for preventing escape of fluid between the ends of the body comprising a plate seated in the inner wall of the body by the fluid pressure within the body and bridging the space between the ends of the body, and keys engaging the ends of said body.

17. A distributing valve for fluid pressure engines comprising a valve body in the general form of a divided ring and adapted to receive fluid under pressure therein and having outlet ports, and means seated in the ends of the body to prevent escape of fluid laterally through the space between the ends of the body, and a bridge plate within the body held by the fluid therein over said space to prevent escape of fluid through said space radially of the body.

18. A distributing valve for fluid pressure engines comprising a valve body in the general form of a divided ring and adapted to receive fluid under pressure therein and having outlet ports, and means carried by one end of the body and bridging the space between the ends of the body to prevent escape of fluid through said space.

19. A distributing valve for fluid pressure engines comprising a valve body in the general form of a divided ring and adapted to receive fluid under pressure therein and having outlet ports, means for preventing escape of fluid in one direction through the space between the ends of the body, and independent means for preventing the escape of fluid in another direction through said space.

20. A distributing valve for fluid pressure engines comprising a valve body in the general form of a divided ring and adapted to receive fluid under pressure therein and having outlet ports located in adjacent relation 105 at one side of said valve body, and a passage in the body to permit escape of back pressure from the engine.

21. A distributing valve for fluid pressure engines comprising a valve body in the general form of a divided ring and adapted to receive fluid under pressure therein and having outlet ports located in adjacent relation at one side of said valve body and a cut out passage on the outer face of said 115 valve body opposite said outlet ports.

22. A distributing valve for fluid pressure engines comprising a valve body in the general form of a divided ring and adapted to receive fluid under pressure therein and having outlet ports located in adjacent relation at one side of said valve body, and a passage in the body opposite said pressure outlet to permit the escape of back pressure from the engine.

23. A distributing valve for fluid pressure engines comprising a valve body in the general form of a divided ring and adapted to receive fluid under pressure therein and having outlet ports located in adjacent re- 130

lation at one side thereof, a cylinder formed in the valve body, a piston in said cylinder operated by the fluid within the valve body, and lever devices operated by said piston and engaged with said valve body adjacent the ends thereof for controlling the expansion of the body under pressure therein.

24. In a fluid pressure engine, the combination of a pressure distributing valve comprising a body in the general form of a divided ring and adapted to receive fluid under pressure therein and having outlet ports, a bushing surrounding said valve body and having ports therein to register with the ports in the valve body, one of said members being movable relatively to the other member, and means for maintaining a constant frictional relation between the valve body and the bushing regardless 20 of variation in pressure within the valve body.

25. In a fluid pressure engine the combination of a pressure distributing valve comprising a body in the general form of a divided ring and adapted to receive fluid under pressure therein and having outlet ports, a bushing surrounding said valve body and having spaced ports to register with said valve body ports, one of said 30 members being movable relatively to the other member, and means within the valve body and adapted to be operated by pressure therein to control the tendency of said valve body to expand with the increase of pressure and to maintain a constant frictional relation between the valve body and bushing under all conditions of pressure.

26. In a fluid pressure engine, the combination of a pressure distributing valve comprising a body in the general form of a divided ring and adapted to receive fluid under pressure therein and having outlet ports, a bushing surrounding said valve body and having ports therein to register with 45 the valve body ports, one of said members being movable relatively to the other member and one of said members having a passage to permit escape of back pressure from the engine.

27. In a fluid pressure engine, the combination of a pressure distributing valve com-

prising a body in the general form of a divided ring and adapted to receive fluid under pressure therein and having outlet ports, a bushing surrounding said valve body and having ports to register with the valve body ports, one of said members being movable relatively to the other member and said valve body having a passage therein to permit escape of back pressure from the 60 engine.

28. In a fluid pressure engine, the combination of a pressure distributing valve comprising a body in the general form of a divided ring and adapted to receive fluid under pressure therein and having outlet ports, a bushing surrounding said valve body and having ports to register with the valve body ports, one of said members being movable relatively to the other member and 65 having a passage between itself and the bushing to permit escape of back pressure from the engine.

29. In a fluid pressure engine, the combination of a pressure distributing valve comprising a body in the general form of a divided ring and adapted to receive fluid under pressure therein and having outlet ports, a bushing surrounding said valve body and having ports to register with the 80 valve body ports, one of said members being movable relatively to the other member, and said valve body being cut out on its outer face opposite the outlet ports to form a passage between itself and the bushing to 85 permit escape of back pressure from the engine.

30. In a fluid pressure engine, the combination of a stationary pressure distributing valve comprising a body in the general form 90 of a divided ring and adapted to receive fluid under pressure therein and having outlet ports, a revoluble crank case, a bushing revolving with said crank case around said valve body, and means within the valve body for controlling the tendency of the body to expand with the increase of pressure therein, whereby a predetermined frictional relation between the valve body and bushing may be substantially maintained 95 under variations of pressure.

WILLIAM E. BAKER.
